Primary Examiner — L. Martinez(74) *Attorney, Agent, or Firm* — Wood Herron & Evans LLP(57) **CLAIM**

The ornamental design for a landscape edging, as shown and described.

DESCRIPTION

FIG. 1 is a front isometric view of a landscape edging, showing our new design;

FIG. 2 is a rear isometric view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is a top plan view with the invention shown in an arcuate configuration.

The broken lines in the drawings illustrate portions of the landscape edging that form no part of the claimed design.
